CAN OPENER

Myron J. Zimmer, Chicago, and Robert B. Paysee,
 Oak Park, Ill., assignors to The Edward Katz-
 inger Company, Chicago, Ill., a corporation of
 Illinois

Application January 26, 1939, Serial No. 252,948

23 Claims. (Cl. 30—8)

This invention relates to a can opener including a traction wheel adapted to engage the bead of a can to be opened and a cutter adapted to be positioned for cooperation with said wheel to cut the head end from a can upon the rotation of the wheel.

It is also an object of the present invention to provide a device of this character which will firmly hold and support the can during the cutting operation, or after as desired.

A further object resides in the provision of a can opener which may be secured to a stationary support and will extend therefrom when in operative position, and may be collapsed into a relatively flat condition against the support when not in use.

This invention also seeks to provide a can opener of this type in which the operation of the cutting mechanism and can supporting means may be controlled through the operation of the collapsing mechanism.

With the above and other objects in view, as will be apparent, this invention consists in the construction, combination and arrangement of parts all as hereinafter more fully described, claimed and illustrated in the accompanying drawing, wherein:

Fig. 1 is a side elevation of a can opener constructed in accordance with this invention with the elements thereof in full line to illustrate position thereof when in operative condition and in dotted line to indicate the position thereof when in collapsed condition, together with a view of an element in dotted line to indicate position thereof when effective to permit movement of the elements into a collapsed condition.

Fig. 2 is a top edge view of the device shown in Fig. 1.

Fig. 3 is a vertical section taken on line 3—3 of Fig. 1.

Reference being had more particularly to the drawing, 10 designates an arm or frame piece arranged at one end on a fixed pivot 11 carried by an arm 12 of a stationary wall mounting plate or bracket 13 suitably fastened by screws 14 or the like to a wall or other support 15. Adjacent its outer or projecting end, the arm 10 is pierced to permit reception of a shaft 17 preferably forming part of a turning crank 18. A knurled traction wheel 19 is secured to the extending end of the shaft 17, which wheel 19 operates closely against the adjoining face of the arm 10. A suitable handle 20 for manipulating the shaft and traction wheel secured thereto, is preferably mounted for rotation on a lat-

erally extending end of the crank 18. It will thus be observed that the traction wheel 19 rotates substantially flush against one face of the arm 10 and that the base or enlarged portion 21a of the shaft 17 bears against the rim or edge of a sleeve or boss 21 either formed integrally with or carried separately by the frame or arm 10 and projecting outwardly from the face of the arm 10 opposed to the face of the arm adjoining the traction wheel 19.

The arm 10 is further pierced by a pivot 22 on which a lever or plate 23 is mounted for movement in a plane substantially parallel to and flush against the face of the arm 10 opposed to the face thereof adjoining the traction wheel 19. The upper edge of the lever or plate 23 is provided with a flange 24 which operates over and against the top edge of the arm 10 as a stop. This flange 24 projects laterally to a point beyond the plane of the outer face of the traction wheel 19, where it is provided with a depending blade or cutter 26. A relatively sharp puncturing point 27 is provided on the blade 26, and the edges of the blade diverge from said puncturing point. For example, on one side of the point 27, the edge slopes upwardly toward the rear limits of the flange 24, while the edge of the blade on the opposite side of the point 27 slopes upwardly toward the front limits of the flange 24, and is preferably bevelled to create a cutting edge.

The lever or plate 23 is movably coupled to the mounting plate 13 through a link 29 arranged in downwardly spaced relation to the arm 10 on a pivot 30 carried by the arm 12 of the member 13 and pivoted as at 31 at its outwardly extending or free end to the downwardly extending portion of the lever 23. The arms 10 and 29, lever 23 and pivots 11, 22, 30 and 31 are preferably arranged and spaced so as to form a mechanism operable upon movement of the arm 10 to permit said arm 10 and link 29 to be swung relative to the mounting plate 13 in an arc of substantially 90 degrees. Furthermore, downward swinging, or movement of the arm 10 into a position of fully extended relation to the mounting plate 13 causes the lever 23 to swing to bring the point 27 of the blade 26 into contact with the head of a can to be opened so that application of pressure downwardly on the arm 10 will cause the point of the blade to puncture the can head and bring the cutting edge thereof into operative position. By rotating the crank 18 by means of the handle 20 and thus causing the traction wheel 19 to turn, the

bead of the can gripped between the blade 26 and the wheel 19 will cause the can to turn relative to the opener, and the head of the can to be completely severed from the side wall thereof. An edge of the link 29 is bent to provide an offset 32 presenting a bearing against which the side wall of a can may ride and be maintained in position to avoid spilling of the can contents during the opening thereof.

A strong tension spring 33 is preferably attached at its ends to a hook formed as at 34 on the arm 10 and a hook 35 on the mounting plate 13. Under the arrangement shown in the drawing, it will be observed that the axis of the spring 33 is adapted to intersect the pivot axis of the arm 10 during movement of the arm 10 and link 29 between collapsed and extended positions. Thus movement of the arm 10 operative to collapse the opener against its support is aided by the tension of the spring 33 when the spring 33 has moved wallward past a line coincident with the axis of the spring and the pivot 11, and movement of the parts to extend the arm 10 for cutting operations, is aided by the spring 33 after the spring has moved downwardly past said line through the axis of the spring and the pivot 11.

For limiting the movement of the arm 10 and its associated members in upright or collapsed condition, under the influence of the spring 33, a stop 36 consisting of a lug bent from the upper edge of the arm 12 of the mounting bracket 13, is provided, against which the arm 10 may be seated. A further locking arrangement may be employed such as a projection 37 formed on the link 29 somewhat forwardly of its pivot 30, which projection is adapted to seat itself in a recess 38 on the base arm 12 when the arm 10 is in seated relation with respect to the stop 36.

The forwardly projecting end of the arm 10 with respect to the lever 23 is provided with a handle 16. The handle 16 consists of a bar or flat strip of metal pivotally fastened to the arm 10 as at 39, where it is disposed edgewise in a vertical plane, and is preferably twisted medially of its length to dispose its free end in a horizontal plane and to which is suitably fastened a button or other finger or hand engaging element 44. The edge of the lever 23 nearest the handle 16 is provided with a locking ear 42. Backward movement of the blade 26 under control of corresponding movement of the lever 23 and arm 10 is limited by a hook 41 on the handle 16 adapted to engage the lower edge of said ear 42 on the lever 23. The hook 41 is preferably bent from an arm or angular extension 40 secured to or formed integrally with the body of the handle 16. An offset 43 extending transversely of the body of the handle 16 presents a shoulder operating against the upper corner defined by the outer end or edge of the arm 10 to limit backward or upward pivotal movement of the handle 16 relative to the arm 10, as shown in dotted lines in Fig. 1. Thus the handle 16 on being lifted into the dotted line position shown in Fig. 1 is operable to engage and lift the arm 10 to release the blade 26 from can cutting position and further to move the arm 10 and its associated mechanism into collapsed condition against the wall 15, while on being depressed into the full line position shown in Fig. 1 is operable, through interengagement of the locking ear 42 and the hook 41, to prevent accidental release of the blade 26 from can cutting position.

As shown in Fig. 1 the forward lower edge of the arm 12 of the mounting plate 13 is preferably

formed to create a claw 48 through which the lower edge of the arm 12 in underlying relation to the pivot 30 serves as a fulcrum point in cooperation with the claw 48 for engaging and removing 5 bottle caps and the like.

In operation, the handle 16 is manipulated to assume a position backward of the dotted line position shown in Fig. 1, whereupon the blade 26 and flange 24 are lifted from the adjoining edge 10 of the arm 10 and traction wheel 19 by the movement of the lever 23 under the influence of the arm 10 and the link 29. With the elements in this position, the edge of the traction wheel 19 is cleared to permit placing of the bead 45 of a 15 can 46 so that the underside of the bead 45 is engaged by the upper edge of the wheel 19. The handle 16 is then depressed until it is moved to cause the point 27 of the blade 26 to come into contact with the head 47 of the can 46. The 20 handle 16 is then further depressed causing the point 27 to puncture the can head and to bring the cutting edge of the blade 26 into operative position. This latter movement of the handle 16 swings the hook 41 into locking engagement with 25 the ear 42 on the lever 23, and the blade 26 is consequently locked against accidental backward or non-cutting movement, without further pressure being required on the handle 16. The handle 20 is then engaged by one hand of the operator 30 who rotates the crank 18 and traction wheel 19. Rotation of the traction wheel 19 causes the edge of the blade 26 to shear the head 47 from the side wall of the can. As this is being done, the blade 26 causes the residuary portion of the head 35 47 still attached to the side wall of the can to be bent downwardly and rest flush against the inner face of the can side wall. When the head has been completely removed from the side wall 40 of the can, the can is still firmly secured between the traction wheel 19 and the flange 24 of the lever 23. When it is desired to remove the can therefrom, the handle 16 may again be moved to the dotted line position shown in Fig. 1 whereupon the locking ear 42 of the lever 23 is disengaged from the hook 41, and thus permit lifting 45 of the arm 10 under the influence of the handle 16 to again clear the blade 26 from the can and proceed to move the arm 10 and its associated elements into collapsed condition, if desired. 50

The invention is not limited to the particular form shown but various modifications are possible within the scope of the following claims.

What is claimed is:

1. A can opener including a support adapted to be attached to a wall, an arm pivotally attached at one end to the support for vertical swinging movement thereon, a traction wheel and cutter carried by the free end of said arm and adjustable toward and away from each other, and means to cause the traction wheel and cutter to approach each other and vice versa upon downward swinging of the arm from a vertical position.

2. A device as claimed in claim 1 in which the arm is mounted for vertical swinging from an upper vertical position to a lower horizontal position, and vice versa, with means for yieldingly holding the arm in its upper position.

3. A device as claimed in claim 1 in which the arm is mounted for vertical swinging from an upper vertical position to a lower horizontal position and vice versa, with means for locking the arm in selected positions.

4. A can opener including a support adapted to be attached to a wall, an arm pivotally mounted

at one end for vertical swinging movement thereon, a traction wheel member and cutter member carried by the free end of the arm, one of said members being carried on a lever pivotally mounted on the arm and adapted to swing to cause relative movement of said members toward and away from each other, and a link connecting said lever and support whereby downward swinging of the arm swings the lever to cause said members to be brought closer together and vice versa.

5. A can opener including a support adapted to be attached to a wall, an arm pivotally mounted at one end for vertical swinging movement thereon, a traction wheel member and cutter member carried by the free end of the arm, one of said members being carried on a lever pivotally mounted on the arm and adapted to swing to cause relative movement of said members toward and away from each other, and a link connecting said lever and support whereby downward swinging of the arm swings the lever to cause said members to be brought closer together and vice versa, and a handle secured to the free end of the arm.

6. A device as claimed in claim 5 in which the handle is movable relative to the arm to selectively limit upward swinging of the arm or release said arm for upward swinging movement.

7. A device as claimed in claim 4 in which the edge of the link is provided with a laterally offset bearing against which the side wall of a can may abut.

8. The combination with a stationary support adapted to be attached to a wall, a relatively flat arm pivotally attached at one end to the support for vertical swinging movement thereon, a lever resting flush against one face of said arm, a flange on one edge of said lever extending over the edge of said arm, a shear blade on the outer end of said flange and projecting downwardly in a plane substantially parallel to the plane of the adjoining face of the arm, a pivotal connection between said lever and said arm, a link pivotally attached at its ends to said lever and said support, a traction wheel mounted for rotation adjoining one end of said arm and having its inner face substantially flush against the face of said arm opposed to the face adjoining the lever and its outer face inwardly from the plane of the shear blade aforesaid, the pivotal attachments of the arm and link to the support and said lever being spaced from each other so that downward swinging of the arm causes the traction wheel and shear blade to approach each other, and vice versa.

9. A device as claimed in claim 8 in which means are provided for maintaining said shear blade and said traction wheel in overlapping relation.

10. A device as claimed in claim 8 in which the arm is mounted for vertical swinging movement from an upper vertical position to a lower horizontal position and vice versa, with means for locking the arm in either of said positions.

11. A can opener including a support adapted to be attached to a wall, an arm pivotally mounted at one end for vertical swinging movement thereon, a traction wheel member and cutter member carried by the free end of the arm, one of said members being carried on a lever pivotally mounted on the arm and adapted to swing to cause relative movement of said members toward and away from each other, an ear on said lever, a link connecting said lever and support whereby downward swinging of the arm swings the lever to cause said members to be brought closer together and vice versa, a handle mounted

on the free end of said arm for movement relative to said arm, and a hook on said handle engageable with the ear on said lever to limit upward swinging of the arm.

12. The combination with a stationary support, of an arm pivotally mounted thereon, a traction wheel and cutter on said arm adjustable toward and away from each other, and means arranged upon swinging of the arm in one direction to cause the traction wheel and cutter to approach each other and upon swinging of the arm in a reverse direction to cause the traction wheel and cutter to be moved apart.

13. The combination with a stationary support, of an arm pivotally mounted thereon, a traction wheel and cutter on said arm adjustable toward and away from each other, means arranged upon swinging of the arm in one direction to cause the traction wheel and cutter to approach each other, and upon swinging of the arm in a reverse direction to cause the traction wheel and cutter to be moved apart, and means operative yieldingly to hold said arm in selected positions corresponding to its limits of movement.

14. The combination with a stationary support, of an arm pivotally mounted thereon, a traction wheel and cutter on said arm adjustable toward and away from each other, means arranged upon swinging of the arm in one direction to cause the traction wheel and cutter to approach each other, and upon swinging of the arm in a reverse direction to cause the traction wheel and cutter to be moved apart, and a spring cooperating with said arm having its axis of tension arranged to intersect the pivotal mounting of said arm during movement of said arm.

15. The combination with a stationary support, of an arm pivotally mounted thereon, a traction wheel and cutter on said arm adjustable toward and away from each other, means arranged upon swinging of the arm in one direction to cause the traction wheel and cutter to approach each other, and upon swinging of the arm in a reverse direction to cause the traction wheel and cutter to be moved apart, and a handle movably mounted on said arm and arranged to resist swinging of the arm when the latter is in a selected position.

16. The combination with a stationary support, means carried thereby for severing the head of a can from the wall thereof including an arm pivotally mounted thereon, a traction wheel mounted on said arm adapted to operate under the bead of a can, a cutter pivoted to said arm and adapted to operate against and through the head of a can adjoining the bead, and means arranged for causing swinging of the arm to actuate the cutter.

17. In a can opener, a base, an arm supported at one end on said base for swinging movements, a feed wheel on said arm, a cutter on said arm movable from and toward the feed wheel and adapted to be forced through the end of a can engaged with said wheel, and means operated through the swinging of said arm in one direction to move the cutter away from the wheel and by the swinging of the arm in the other direction to cause the cutter to puncture the end of a can operatively engaged with said wheel.

18. In a can opener, a base, an arm supported at one end on said base for swinging movements from a working position to an idle position, a feed wheel on the other end of the arm, a cutter

mounted on the arm for movements from and toward the feed wheel, and means to cause said cutter to move from and toward said wheel when said arm is oscillated.

19. In a can opener, a base, an arm projecting from and supported at one end on said base for swinging movements from a working position to an idle position, a feed wheel on the arm, a second arm hinged to and projecting from said base, a cutter, and means connecting the cutter and said arms together to cause the cutter to move away from said wheel when the arm is swung toward its idle position and to move toward the wheel when the arm is swung toward its working position.

20. In a can opener, a base, an elongated member supported at one end on said base for swinging movements, a feed wheel on said member, a cutter, a second elongated member supported at one end for swinging movements about an axis parallel to and spaced apart from the axis about which the first member swings, and connections between both of said members and the cutter to cause the cutter to move away from the wheel when said members are swung in one direction and toward the wheel when said members are swung in the other direction.

21. In a can opener, a base, an elongated member supported at one end on said base for swinging movements, a feed wheel on said member, a second elongated member supported at one end on said base for swinging movements about an axis parallel to and spaced apart from the axis about which the first member swings, a cutter mounted on said second member, and connections between said members to cause the

cutter to move away from the wheel when said members are swung in one direction and toward the wheel when said members are swung in the other direction.

5 22. In a can opener, a base, an elongated member supported at one end on said base for swinging movements, a feed wheel on said member, a cutter movably mounted on the aforesaid member and adapted to be forced through 10 the end of a can engaged with said wheel, a second elongated member supported at one end on said base for swinging movements about an axis parallel to and spaced apart from the axis about which the first member swings, and a 15 connection between said second member and the cutter to cause that member to move the cutter away from the wheel when said members are swung in one direction and to cause the cutter to puncture the end of a can operatively engaged with said wheel when said members are swung in the other direction.

20 23. In a can opener, a support, an elongated member hinged at one end to said support for vertical swinging movements, a feed wheel on the other end of said member, a handle for turning said wheel, a second elongated member similarly hinged to said support at a point below the hinged axis for the first member, a cutter device mounted on the first member for rocking movements from and toward said wheel, and a connection between the second of said 25 members and the cutter device to cause the latter to rock when said members are oscillated.
